United States Patent Office.

HORACE B. HOOKER, OF ROCHESTER, NEW YORK.

Letters Patent No. 102,269, dated April 26, 1870.

SKATE-FASTENING

The Schedule referred to in these Letters Patent and making part of the same.

To all whom it may concern:

Be it known that I, HORACE B. HOOKER, of Rochester, in the county of Monroe and State of New York, have invented certain new and useful Improvements in "Skates;" and I do hereby declare that the following is a full, clear, and exact description thereof, reference being had to the accompanying drawings making part of this specification, in which—

Figure 1 is a plan view of my invention.

Figure 2 is a sectional elevation of the toe-plate.

Figure 3 is a vertical longitudinal section of the heel-plate.

Figure 4 is an inverted view of the same.

The object and nature of my invention will be understood by reference to the specifications and drawings; and, to enable others to make and use the same, I will describe its construction and operation.

The clasping-device on the heel-plate C is pivoted upon the bolt c, figs. 1 and 3, which has a T-head entering a transverse slot in the runner A.

This clasp is composed of the heel-rest a, provided with lugs b at the rear, and the sliding clamp f, bent up at the front, as shown.

These rest upon the plate d, provided with lugs e, which are bent down to clasp the runner, as shown in fig. 4.

The countersunk nut i on the bolt c extends through the plates a and f, and binds the plate d to the runner, allowing a and f to turn freely.

A link, m, is pivoted at one end to the fixed plate d, eccentrically to the bolt c, as shown in fig. 4, and at the other to the sliding clamp f, by means of the bolt n.

This latter has a countersunk head, fitted to slide in a slot formed in the heel-rest a, and its shank is made flat upon two opposite sides, as shown in fig. 5.

The flattened portion enters a slot in the clamp f, and the nut p, having a short cylindrical projection upon its inner side, binds the bolt tightly to the clamp f, and makes it adjustable thereon, while the link m is allowed to turn freely upon such cylindrical projection, as indicated in fig. 3.

It will be observed that, when the heel-plate and runner are turned at an angle with each other, the link m pushes the clamp f forward to receive the heel of the boot, as shown in dotted lines in fig. 4, and, when returned to their parallel position, the runner A acts as a clamping-lever upon the heel-plate.

Upon the toe-plate B, I provide the clasps b', shown extended in fig. 1, pivoted to the plate a', by means of bolts n', and bent up so as to clasp the sole of the boot.

These clasps are operated transversely to the runner A, by means of the links m' pivoted upon the

bolts n', and to an oscillating disk, d', to which is attached the locking-lever l.

The links m' are of such a conformation that, when shut together by the lever l, as indicated by dotted lines in fig. 1, they form a continuous plate, upon which the boot rests.

The plate a' rests upon and is properly secured to a smaller plate, h, which, in turn, is attached to the runner, by a bolt, o, similar to c in the heel-plate, and upon which the disk d' is pivoted.

The pivoting points of the links m', upon the disk d', are so located that, when the boot is clamped, said pivots t are forced slightly past a line drawn through the centers of the bolts n', whereby the clasps b' are locked, and the strain taken off the lever l.

The lever l is constructed of steel, or other elastic material, and is so formed as to spring over upon the toe of the runner, by means of a suitable jaw, l', or other similar device, as shown in fig. 2.

The bolts n' are constructed like n, and the clasps b' are adjustable upon them, in the same manner as the clamp f, independently of the clamping-lever and links, to accommodate different-sized boots.

It will be observed that the lever l is located in such a position under the foot of the wearer, that it is impossible for it to become accidentally unlocked, and at the same time it is convenient of access for fastening or unfastening the skate.

The clasping device shown upon the heel-plate is equally applicable to the toe-plate.

My improvements may be attached to any form of runner in use.

What I claim as my invention, and desire to secure by Letters Patent, is—

1. The runner A, in combination with the eccentrically-pivoted link m, or other device for operating the sliding pivoted clasping-plate f, by a horizontal lateral movement of said runner.

2. The link m, in combination with a sliding pivoted clasping-plate on the runner A, operating substantially as herein shown and described.

3. The arrangement of the pivots t upon the disk d', with relation to the links m', whereby the clasps b' are locked, as said pivots are forced slightly past a line drawn through the centers of the bolts n' and disk d', substantially as described.

4. In combination with the swiveled heel-clasp f a, operating substantially as described, the lever l, clamping over the toe of the runner, and between it and the foot of the wearer, whereby both ends of the skate may be clasped upon the foot at one operation.

H. B. HOOKER.
